UNITED STATES PATENT OFFICE.

LOUIS D. SUMMERS, OF SPRINGFIELD, ILLINOIS, ASSIGNOR TO FRANZ AND SUMMERS, OF SPRINGFIELD, ILLINOIS, CONSISTING OF FRED J. FRANZ, WILLIAM J. FRANZ, AND LOUIS D. SUMMERS.

HOT-WATER AND STEAM HEAT ECONOMIZER FOR FURNACES.

Application filed May 13, 1927. Serial No. 191,056.

My invention relates to a class of heat economizers adapted to be operated on the counterflow principle and be operatively connected with a furnace particularly of the hot water or steam type; an object being in this device particularly to secure by means of its novel construction and operative relation to a furnace to which it is adapted to be connected, a maximum of benefit from the heated products of combustion normally passing out of the furnace flue as wasted heat.

A further object of this invention is to provide additional heating surface as well as to provide an economizer for operative connection with a furnace that will temporarily retain the products of combustion emanating from the furnace within a chamber for their accommodation through which a series of hot water pipes extend in accommodating the passage of cooler water from a lower water chamber to an upper hot water or steam chamber as it becomes quickly heated in passing through the pipes.

Where low pressure steam heat is desired a suitable water level may be, of course, maintained thus providing in the upper head of the economizer a super-heating steam chamber.

A further object of my invention is to provide a hot water and steam heat economizer for furnaces to be used preferably with oil or gas burning furnaces and the like and such as will be adapted to take advantage of the control of the movement of the products of combustion normally passing out of a furnace flue as wasted heat; and in this economizer I have for a further object to so control the movement of gases emanating from a furnace as to make it possible to most effectively transfer the greatest possible percentage of heat of the gases to the circulating water passing through the water heads and tubes of the economizer during the process of heat transfer while the products of combustion are still at their highest temperature; while in the meantime I provide in a heating operation means for prolonging the time during which the hot gases will continue to heat the water circulating through the hot water tubes extending through the gas chamber.

My invention embodies a design and construction of hot water and steam heat econo-

mizers that is adapted to be made of metallic parts such as sheet iron and the like together with such other details of construction and arrangement as will combine the merits of strength and relation of parts for

55

60

The intended novel features of construction and design of my device will be hereinafter more fully described in the annexed specifications, recited in the claims, and illustrated in the accompanying drawings

65

in which like reference numerals indicate like parts in the several figures.

Referring to the figures:

Fig. 1. is a side elevation of the hot water and steam heat economizer of my invention illustrating the manner in which the same is connected with a hot water and steam furnace and in this figure both the hot water connections and cold water connections as well as the connections for the hot products of combustion are disclosed.

70

Fig. 2. is a side elevation of the heat economizer of my invention shown detached from the furnace with which it is normally connected.

80

Fig. 3. is a side elevation of the heat economizer of my invention shown with the detachable metallic expansive jacket removed from about the gas chamber of the heat economizer.

85

Fig. 4. is a side elevation of the hot water and steam heat economizer of my invention disclosing, by a cut-away, the details of the economizer's construction.

90

Fig. 5. is a vertical section M—M Fig. 2. of the economizer.

Fig. 6. is a horizontal cross section N—N Fig. 2. exposing to view a possible arrangement of the hot water tubes in their space relation.

95

The preferred embodiment of my invention and the method of securing the desired results therewith will now be pointed out as references are made to the several numerals in the respective figures illustrating the device of my invention.

100

Among other successful arrangements by which intended results may be secured with the hot water and steam heat economizer of my invention is an arrangement illustrated in the accompanying drawings whereby the hot water and steam heat economizer —1— Fig. 1. is spaced from but operatively con-

105

2
nected with a hot water furnace —2— by both hot water and hot gas connections.

A particular merit of my invention may be observed in the fact that flue pipe —3— of hot water and steam furnace —2— connects directly with the upper area of the gas chamber of the economizer —1— to which it carries the heated products of combustion from hot water and steam furnace —2— 10 where the hot gases come into gas chamber —10— (see Fig. —4—) through flue pipe —3— coming into forceful contact with hot water pipes —11— where the hot gases thus strike hot water pipes —11— at a point near 15 the top of the pipes just before the hot water within the pipes would rise into upper hot water chamber —12— just before the water leaves the upper chamber through pipe —6— to join with the hot water in pipe 20 7 (see Fig. —1—) before circulating out over the hot water heating system.

In this manner it will be seen that the hot gases reaching chamber —10— from the hot water furnace —2— through flue pipe —3— 25 reach this chamber when said gases are approximately at their highest temperature just where the hottest application may be most effectively applied to the heating water rising in the pipes just before the water or 30 steam therefrom is ready to be distributed throughout the heating system.

Every hot water system has a cold water return in the circulating system adapted to return the water after it is cooled to the 35 lower portion of the boiler. This return pipe is not shown in Fig. 1, but a cold water pipe —5— connects the lower area of the boiler in furnace —2— with lower water chamber —13— through which the cold 40 water entering the economizer through drum —9— forming chamber —13— rises through hot water tubes —11— with an accelerating velocity until it reaches upper chamber —12— from which it is distributed through 45 pipe —7— of the hot water furnace.

To those skilled in the art to which this economizer pertains it will be observed that this novel and efficient as well as speedy method of heating and distributing water or 50 steam in this manner is accomplished in the following way: When the gases from flue pipe —3— forcibly enter chamber —10— accommodating the heated products of combustion they enter the upper area thereof 55 and can only move in one direction upon entering this chamber and that is downward; and move downward through heat stratification; and by actual test it has been shown that while these gases are settling 60 downward in the gas chamber they gradually give up a great percentage of their heat before passing out of pipe —4— to the chimney.

It will therefore be seen that while the 65 gases through this process are gradually set-

ting to a lower level in the economizer and giving up their heat as they settle and also settling because they are giving up their heat and getting cooler, that the water in the meantime entering in bottom chamber —13— gets its first application of heat as it reaches the level of the bottom of the gas chamber of the economizer where the gases are at their lowest temperature; and then as the water rises in the tubes to 75 the level of the hotter gases it reaches the hottest point at the top entering the hot water dome —12— before leaving the economizer as hot water or steam.

Attention is called to Fig. 3 which exposes to view the upper and lower water chambers and their connecting water tubes. This is shown by the removal of jacket —1— which when secured into operative position forms the gas chamber about pipes —11—. 85 This jacket is detachably secured into place normally by bolts —15—.

In a careful study of the details of structure of my economizer those who are skilled in the heating art will observe a novel arrangement of details of construction of my economizer which make it possible to secure therewith new and novel results.

In this connection attention is directed to the manner in which jacket —1— is 95 adapted to be detachably secured about the periphery of the upper and lower heads —8— and —9— of the economizer thus to provide an expansible detachable closure member forming a gas chamber for the 100 economizer.

To heating engineers it will be evident that when the hot products of combustion emanating from the furnace are admitted into the gas chamber —10— of the economizer that these gases commonly range from two or three hundred degrees to a thousand or more degrees of temperature while at the same time the tubes and water chambers would not carry such a high temperature 110 when they contain water or steam perhaps up to 250° and the differential in temperature obtaining within the economizer would cause a decided expansion of jacket —1— under such conditions when this jacket 115 forms the gas chamber since this jacket does not come in contact with the water within the economizer.

It is therefore evident that when this outside jacket does expand lengthwise or otherwise that if this jacket was riveted or bolted to the heads —8— and —9— and then expanded when forming the gas chamber with such high gas temperatures that the strain of the expanding jacket would cause the tubes —11— to pull out of the upper or lower heads to which they are attached; but in my economizer I detachably secure jacket —1— about the upper and lower heads —8— and —9— in such a way as will permit the 120

jacket to slidably move on these heads when it expands and thus avoid any of the unfortunate consequences that might result from rigidly securing the jacket to these heads.

This economizer is adapted to be supported on legs —14—.

To those skilled in the heating art it will be evident that certain changes may be made in the structure of my economizer and still stay within the spirit and scope of my invention; but the preferred arrangement of details is illustrated in the drawings forming a part of this specification.

Having thus described the nature of my invention what I claim as new and useful and desire to secure by Letters Patent is:

1. A hot water and steam heat economizer adapted to be spaced from and operatively connected with an oil or gas burning hot water or steam furnace, comprising an upper and a lower water head connected by a plurality of communicating upright water tubes; said heads having a horizontal diameter in excess of the diameter of the horizontal cross sectional plane enclosing the tubes; a detachable metallic jacket engaging and encompassing said upper and lower heads of the economizer forming a gas chamber for the economizer and adapted to slidably move when expanding longitudinally upon the outer walls of said heads; said gas chamber provided with an upper wall opening in the expanding jacket adapted to be communicatively connected with the flue gases from a furnace and said chamber further provided with a lower wall opening in the enclosing jacket adapted to establish communication between said gas chamber and an outlet flue; said lower water head adapted to be communicatively connected with the cold water level of a hot water and steam heat furnace and said upper water or steam head adapted to be communicatively connected with the hot water or steam level of a hot water and steam heating furnace.

2. A hot water and steam heat economizer of the character described adapted to be operatively connected with an oil or gas burning hot water and steam heating furnace comprising in combination a lower cold water head having a bottom opening adapted to admit cold water from a boiler; a spaced upper hot water and steam head having a central opening to discharge hot water and steam and adapted to be communicatively connected with a hot water and steam lead pipe from a furnace; said heads of the economizer communicatively connected by a plurality of upright spaced water tubes; an upright metallic detachable casing encompassing and loosely engaging said upper and lower heads forming a gas chamber between said heads; said casing adapted to slidably move on said heads when expanded by heat and provided with an upper inlet wall opening for hot products of combustion adapted to be operatively connected with a furnace flue; said casing further provided with a lower outlet wall opening adapted to establish outlet communication with a house flue for said gases after giving up a portion of their heat to said water tubes within said gas chamber.

In witness whereof, I hereby set my hand 75
this 9th day of May 1927 A. D.

LOUIS D. SUMMERS.
